UNITED STATES PATENT OFFICE.

FREDERICK C. HERSEE, OF ROSLINDALE, MASSACHUSETTS, ASSIGNOR TO MOTOR SPECIALTIES COMPANY, A CORPORATION OF MASSACHUSETTS.

DESIGN FOR A WHEEL-PULLER.

45,459.

Specification for Design.

Patented Mar. 24, 1914.

Application filed December 29, 1913. Serial No. 809,421. Term of patent 3½ years.

To all whom it may concern:

Be it known that I, FREDERICK C. HERSEE, a citizen of the United States, residing at Roslindale, in the county of Suffolk and Commonwealth of Massachusetts, have invented a new, original, and ornamental Design for Wheel-Pullers, of which the following is a specification, reference being had to the accompanying drawing, forming part thereof.

The figure is a perspective view of a wheel puller, showing my new design.

The outer surface of the device is preferably, though not necessarily, more or less roughened as shown.

I claim:

The ornamental design for a wheel puller, as shown.

FREDERICK C. HERSEE. [L. S.]
